CONTAINER AND PACKAGE FOR MATCHES
AND THE LIKE

William Homer Colgate, Larchmont, N. Y.

Application August 3, 1933, Serial No. 683,442

15 Claims. (Cl. 206—44)

The present invention relates to containers or packages and embodies, more specifically, an improved form of package for articles, such as books of paper matches, etc. The invention further embodies, more particularly, an improved form of package wherein the indicia upon the covers of such books may be fully exposed to view without destroying the security of the package against loss and displacement of the individual books thereof.

10 In applicant's copending application, Serial No. 652,136, filed January 17, 1933, a form of package is shown and described wherein a number of books are placed side by side in such fashion that a desired display surface formed by a number of the books is provided. The present invention embodies an improved form of package by means of which the books are maintained in a predetermined relationship more effectively than in previous constructions, the structure being such as to be readily manufactured and further enabling the packaging operations to be performed with a minimum of effort.

15 In addition to the foregoing, it is a further object of the invention to provide a container or package for books of the above described character wherein the individual books of a package may be effectively positioned in packaged relationship and against displacement, the surfaces of the books being effectively exposed to view and the package being of such construction as to afford adequate reenforcement against all stresses tending to damage or disarrange the contents thereof.

20 Further objects of the invention will be apparent as it is described in further detail in connection with the accompanying drawings, wherein—

25 Figure 1 is a plan view of the package constructed in accordance with the present invention, the wrapper of the package being shown in section, the section being taken on the line 1—1 of Figure 2, and looking in the direction of the arrows.

30 Figure 2 is a view in section, taken on line 2—2 of Figure 1, and looking in the direction of the arrows.

35 Figure 3 is a plan view of the reenforcement prior to the bending thereof.

40 Figure 4 is a view in end elevation showing the reenforcement of Figure 3 after bending.

45 Figure 5 is a plan view of a package provided with a modified form of reenforcement.

50 Figure 6 is a plan view of the reenforcement shown in Figure 5 prior to bending the same,

Figure 7 is a view in side elevation showing the bent reenforcement of Figure 6.

5 Figure 8 is a view in end elevation showing the reenforcement of Figure 7.

Figure 9 is a view in section, taken on line 9—9 of Figure 5, and looking in the direction of the arrows.

5 Figure 10 is a partial bottom view of the reenforcement of Figure 5.

10 Figure 11 is a plan view showing a container forming a package of modified construction.

Figure 12 is a view similar to Figure 11, showing the elements of the container bent into packaging position.

15 Figure 13 is a view similar to Figure 12, showing the container filled and wrapped, the wrapping being shown in section on line 13—13 of Figure 14, and looking in the direction of the arrows.

20 Figure 14 is a view in section, taken on line 14—14 of Figure 13, and looking in the direction of the arrows.

Figure 15 is a view in end elevation of the container shown in Figure 12.

25 Figure 16 is a plan view, showing a further modified form of the container.

Figure 17 is a plan view of the container of Figure 16 bent into packaging position.

30 Figure 18 is a plan view, similar to Figure 17, showing the container properly packaged and wrapped, the wrapping being shown in section.

Figure 19 is a view in section, taken on line 19—19 of Figure 18, and looking in the direction of the arrows.

35 Figure 20 is a view in end elevation, showing the package of Figure 19, the wrapping being shown in section.

Figure 21 is a plan view, showing a modification of the container shown in Figure 16.

40 Figure 22 is a plan view, showing the positioning structure of Figure 21 prior to the bending thereof.

45 Figure 23 is a side view, showing the manner in which the container of Figure 21 positions the contents thereof.

Referring to Figures 1, 2, 3 and 4, a package is shown composed of eight books, designated by the reference character 30. These books are enclosed within a wrapping 31, which is preferably transparent and may be formed of "Cellophane".

50 The books comprising the package, of course, may be any desired number in multiples of two and are placed end to end in any desired number of layers. These end to end placed books may be combined with similarly placed layers at the

sides thereof to give the package a desired depth as well as width. Intermediate the ends 32 of the package, a Z-shaped positioning bar 33 is placed, the bar being formed of a transverse wall member 34 and flaps 35, which are adapted to be bent into planes substantially at right angles to the wall 34 to overlie the adjacent portions of the contents of the package, as illustrated in Figure 2. In this fashion, the positioning bar not only adds rigidity to the package but serves as an effective means for positioning the contents thereof when packaged.

Referring to the construction shown in Figures 5, 6, 7, 8, 9 and 10, the wrapping may enclose the books shown in Figure 1, and a modified form of positioning member is provided comprising a reinforcement 36 formed with a retaining portion 37 upon an edge 38 of which a flap 39 is formed to be folded at right angles to the portion 37 and position the contents of the package against endwise displacement. A tab 40 is preferably formed as a continuation of the portion 37 and is adapted to overlie a portion of the contents at one end thereof, as shown in Figure 5.

25. The positioning member is further provided with a side wall 41 and a bottom strip 42 which is adapted to be folded down and back to lie parallel to the portion 37. The position of these elements is clearly shown in Figures 7, 8, 9 and 30. 10.

35. The construction shown in Figures 6 through 10 thus will be seen to afford an effective means for preventing endwise displacement of the contents of the package as well as lateral displacement in a plurality of directions.

40. In the construction shown in Figures 11, 12, 13, 14 and 15, a modified form of the invention is illustrated, this construction comprising a container formed from a blank 43, which may constitute the bottom and side walls of the container. The blank is scored as indicated by dotted lines 44 and cut as indicated by solid lines 45. The cuts thus form side flaps 46 and end flaps 47 which, when turned into planes at right angles to the bottom of the container, form side and end walls therefor.

45. The blank 43 is cut away at 48 and 49 and formed with a transverse positioning strip 50, along one edge of which a flap 51 is hinged. A tab 52 is preferably formed on the strip 50 and flap 51 is provided with an additional flap 53, which is formed with a tab 54, which is adapted to lie parallel to tab 52 when the flaps 51 and 53 are bent into positions shown in Figure 14.

50. Figure 12 shows the container of Figure 11 after the side and end walls, as well as the flaps, have been bent into packaging position.

55. Figures 13 and 14 illustrate the container of Figure 12 after the same has been packaged, and further show the manner in which the flaps 51 and 53 position the contents of the package against endwise displacement as well as laterally thereof.

60. Figures 16, 17, 18, 19 and 20 show a modified form of container, which is adapted to be formed from a blank 55, the blank being scored as indicated by dotted lines 56, 57, 58 and 59, and cut as indicated at 60 and 61. Folding the blank on the scored lines 56 causes side flaps 62 thereof to form the sides of the package, notches 63 being provided to facilitate the securing of the sides together. Prior to engaging the notched portions of the flaps 62, the scored portions 57 are bent, the end webs 64 of the blank being 70. 75. swung in opposite directions, as illustrated in

Figure 19. These end portions of the blank form end positioning walls and cut portions 60 of such walls extend upwardly beyond the extensions 65 of the blank to prevent endwise displacement of the contents of one side of the package. The intermediate portion or central web 66 of the blank, after folding upon the scored lines 58, constitute a transverse intermediate wall having extensions 67 terminating in the scored lines 59. The extensions 65 are hinged to the opposite sides of the web 66 along the scored lines 58. Flaps 68 are folded into parallel relationship along the scored lines 59 and serve as means for preventing displacement of the contents of the package out of the plane thereof.

15. In the form of the construction shown in Figures 21, 22 and 23, the flaps 68 are provided with tabs 69, which afford an additional positioning element to prevent displacement of the entire contents of the package out of the plane of the package. As will be seen from the cross-sectional view of Figure 23, the perpendicular partition is only formed with right angular flanged portions overlying the adjacent ends of the books upon one side of the partition and at an edge thereof, but a tab is struck out of the partition and is adapted to lie in a plane of each of the flanged portions in order that the books upon each side of the partition and at each edge thereof may be held in position.

20. From the foregoing it will be seen that a package has been provided by means of which the contents thereof are effectively maintained in position against displacement in certain directions.

25. While the invention has been described with reference to the constructions shown specifically herein, it is not to be limited save as defined by the appended claims.

30. I claim as my invention:

40. 1. A package for match books and the like comprising a plurality of books disposed end to end, a wrapping therefor, and a reinforcing and positioning member between the adjacent ends of the books, said reinforcing member having 45 positioning strips hinged to sides thereof and adapted to fold down over certain of the books, one of the positioning strips having a portion formed thereon forming an apertured bottom for the package.

50. 2. A reinforcing and positioning form for match books and the like comprising a central web having extensions hinged to opposite edges thereof, end webs hinged to the ends of the last named extensions and side flaps hinged to the opposite sides of the last named webs.

55. 3. A reinforcing and positioning form for match books and the like comprising a central web having extensions hinged to opposite edges thereof, end webs hinged to the ends of the last named extensions, extensions on the first named web, and flaps hinged to the last named extensions.

60. 4. A reinforcing and positioning form for match books and the like comprising a central web having extensions hinged to opposite edges thereof, end webs hinged to the ends of the last named extensions, and shoulders on the end webs.

65. 5. A reinforcing and positioning form for match books and the like comprising a central web having extensions hinged to opposite edges thereof, end webs hinged to the ends of the last named extensions, extensions on the first named

- web, and flaps hinged to the last named extensions, and shoulders on the end webs.
6. A reinforcing and positioning form for match books and the like comprising a central web having extensions hinged to opposite edges thereof, end webs hinged to the ends of the last named extensions, extensions on the first named web, flaps hinged to the last named extensions, shoulders on the end webs, and side flaps hinged to the opposite sides of the last named webs.
7. A package for match books and the like comprising a plurality of books disposed end to end, and a reinforcing and positioning member between the adjacent ends of the books, said reinforcing member having positioning strips hinged to sides thereof and adapted to fold down over certain of the books, one of the positioning strips having a portion formed thereon forming an apertured bottom for the package.
8. A package for match books and the like comprising a plurality of books disposed end to end, and a reinforcing and positioning member between the adjacent ends of the books, said reinforcing member having positioning strips hinged to sides thereof and adapted to fold down over certain of the books, one of the positioning strips having a portion formed thereon forming an apertured bottom for the package, and means to hold the books on the member.
9. A display package comprising a plurality of match books or the like arranged flatwise in two parallel rows separated by a perpendicular partition, said partition having a right angular flange overlying the adjacent edge of one of said rows and a right angular flange underlying the adjacent edge of the other of said rows, and a transparent wrapper tightly enclosing and embracing the match book assembly.
10. A display package comprising a plurality of match books or the like arranged flatwise in two parallel rows separated by a perpendicular partition, said rows being arranged in two or more layers of books alternately reversed, said partition having a right angular flange overlying the adjacent edge of one of said rows, and a right angular flange underlying the adjacent edge of the other of said rows, and a transparent wrapper tightly enclosing and embracing the match book assembly.
11. A display package comprising a plurality of

match books or the like arranged flatwise in two parallel rows separated by a perpendicular partition, said partition having a right angular flange overlying the adjacent edge of one of said rows, and a transparent wrapper tightly enclosing and embracing the match book assembly.

12. A display package comprising a plurality of match books or the like arranged flatwise in two parallel rows separated by a perpendicular partition, said partition having a right angular flange overlying the adjacent edge of one of said rows, and a right angular flange underlying the adjacent edge of the other of said rows, one of said right angular flanges being formed with a tab which projects in the plane of the flange beyond the perpendicular partition, and a transparent wrapper tightly enclosing and embracing the match book assembly.

13. A container comprising a reinforcing and positioning member adapted to lie between a plurality of articles held by the container, said reinforcing member having positioning strips hinged to sides thereof and adapted to fold down over certain of the articles, one of the positioning strips having a portion formed thereon forming an apertured bottom for the container.

14. As an article of manufacture, a reinforcing and positioning member forming a single wall upon the opposite sides of which package contents are adapted to abut directly and having a positioning strip hinged to one side thereof and a tab on the positioning strip extending on the opposite side of the positioning member from the strip and formed by pressing out a portion of the positioning member.

15. A container comprising a reinforcing and positioning member adapted to lie between a plurality of articles held by the container, said reinforcing member having a positioning strip hinged to one side thereof and adapted to fold down under certain of the articles, the reinforcing member being cut out of the material of the positioning strip, the strip having an apertured portion formed by the positioning member and by an additional portion of the material of the strip which is cut away to form an enlarged aperture through which contents of the container may be viewed.
